UNITED STATES PATENT OFFICE

GEORGE E. OLSEN, OF GREEN BAY, WISCONSIN

PROCESS FOR CLEANING FABRICS

Application filed November 18, 1929. Serial No. 408,120.

This invention relates to a new and improved process and apparatus for cleaning and spotting fabrics.

One of the objects of my invention is the provision of an improved process and apparatus for cleaning fabrics and includes an especially designed machine for utilizing gasoline, naphtha or other cleaning fluids employed in removing spots, water marks, 10 perspiration, and the like from garments, drapes and fabrics regardless of their texture.

Another object of my invention is the provision of a novel process and apparatus 15 wherein the garments are first run through naphtha, gasoline, or a similar fluid to form a protection for the fabrics, and is then run through chemically treated water which contains chemicals having properties for removing dirt and stains, as well as forming protection to the color and the fabric, and then 20 agitating the water thoroughly through the fabric in order to remove all dirt, spots, stains, and the like after which it is drained 25 and partially dried before being hung out for thorough drying.

A further object of my invention is the provision of an improved apparatus utilizing both water and gasoline, or other similar solvent in the cleaning operation, thus 30 materially increasing the efficiency of cleaning and removing spots, water marks, perspiration, food marks, etc., from fabrics which the organic substance will not remove.

A still further object of the invention is the provision of an improved apparatus for carrying out the novel process referred to above which consists of a tank having suitable inlets, drainage and overflow, together 35 with a foraminous container with means for raising and lowering the container within the tank.

With the above and other objects in view, the invention consists in the novel features 40 of construction, the combination and ar-

rangement of parts hereinafter more fully set forth, pointed out in the claims and shown in the accompanying drawings wherein:

Figure 1 is an elevation of an apparatus carrying out my improved process;

Figure 2 is a detail section of the body of the apparatus, illustrating in plan view the air supply control;

Figure 3 is a vertical section view with parts disclosed in elevation;

Figure 4 is a detail section on the line 4-4 of Figure 3.

For carrying out my improved process, I provide a main tank 1 having suitable supporting legs 2, and at one side of the tank, I provide a tubular upright 3 in which is slidably mounted a plunger 4, the upper end of the plunger having attached thereto the arm 5 of a standard 6. The lower end of the standard 6 is connected to a wire basket 7 having a hinged cover 8.

In order to properly support the basket 7 with respect to the standard 6, I provide a yoke 9, the upper end of which is pivotally connected to the standard adjacent the arm 70 5, while the lower ends are connected to the basket 7 upon opposite sides thereof.

The tubular standard 3 is arranged vertically of the tank 1 and retained in place by means of the guides 10. The lower end of the 75 tubular member 3 is connected to a compressed air supply pipe 11 provided with a control valve 12 whereby compressed air is utilized for raising the plunger 4 into the tubular member 3.

At one side of the tank 1, I provide a pair of gauges 13 and 14, and it will be noted that upon the interior of the tank, I have indicated the lines 15 and 16, the line 15 indicating the high mark of the chemically treated water to be used in the tank and this high mark 15 can be readily noted by the gauge 13 so that the proper quantity of water can be placed in the tank for carrying out the process.

The line 16 indicated in Figure 3 within the tank can be gauged from the exterior of the tank through the medium of the gauge 14, and this line indicates the high mark for the naphtha, gasoline, or similar fluid. At 5 17, I have indicated an overflow pipe through which is discharged in superfluous amounts of naphtha, gasoline or the like, so that only a certain amount will be maintained in the 10 tank.

Within the bottom of the tank, I provide a substantially U-shaped perforated air pipe 18, the horizontal part of which extends diametric of the tank and retained in position 15 by means of the guide 19. One end of the pipe 18 is connected to the supply pipe 20 in which is arranged a valve 21. The stem of the valve 21 has a crank arm 22 connected to the lateral arm 23 of a reciprocating rod 20 24. The rod 24 has a lateral foot piece 25 at its lower end and the movement of the rod is guided by the stationary loops 26 within the tank.

The rod 24 is normally maintained in a 25 raised position and the valve 21 is normally closed by means of a coil spring 27, one end of which is attached to the crank arm 22 and the other end attached to a lateral arm 28 on the pipe 20 adjacent the valve 21.

30 The apparatus heretofore described is used in my improved process for cleaning and spotting fabrics and in carrying out the process, the fabrics are placed in the wire basket 7 and the basket is then lowered through the 35 naphtha, gasoline, or the like, the fabrics being saturated with the same to form a protection therefor, and when the basket is lowered sufficient to engage the foot piece 25 and pushed downwardly into the water, the valve 21 is opened through a reciprocation of the 40 rod 24 against the tension of spring 27. This admits air under pressure into the tank for agitating the chemically treated water for forcing the same through the fabrics in the 45 basket.

This action is carried on for a certain 50 length of time and then the basket is raised by admitting air under pressure into the tubular standard 3, forcing the plunger upwardly which in turn will raise the basket.

At this time, it might be well to call attention to the fact that water to the tank 1 is supplied through a pipe 29 which extends into the tank just above the overflow 17, 55 while gasoline, naphtha, and the like can be supplied to the tank through the supply pipe 30 which can be arranged directly above the water supply 29, or in any other suitable position.

60 It will be noted that any gasoline removed from the basket and its contents, while the same is agitated, in the water, will rise upwardly into the gasoline area as the naphtha, gasoline and similar fluid will not mix with the water, this assuring the fact that the

naphtha, gasoline, and the like, will always be on top of the water and the fabrics in the basket will be treated as described, with naphtha or gasoline before being submerged in the water.

70 The water used in the bottom of the tank is chemically treated with any suitable chemicals contained therein for removing dirt and stain qualities, and also chemicals for the protection of the coloring of the fabric and 75 for the fabric itself, thus fabrics within the basket can be thoroughly cleaned and any spots, water marks, perspiration, food marks, and the like, will be quickly removed from the fabrics.

80 It will also be noted that by using this process, it will not be necessary to remove the trimmings from dresses and similar articles, as no injurious fluid is used and furthermore, the fabrics of which the trimmings 85 may be constructed will be protected through the saturation of these articles with the gasoline or naphtha. In view of the fact that the fabrics being cleaned are first dipped in naphtha or the like, the dirt spots are naturally softened to a certain extent and, therefore, it will not be necessary to have the garment remain in the water solution any great length of time, particularly in view of the 90 fact that the water solution is slightly agitated through the use of compressed air for quickly removing the dirt and stains from the fabrics. It will be readily appreciated, that by having the fabric first treated with naphtha, gasoline or the like, to thoroughly 95 saturate the fabric with such a fluid, the chemically treated water will not penetrate the fabric, but will have a tendency to remove from the exterior of the fabric any dirt or stains, and from this, it will be noted that 100 my improved process is extremely useful, not only from a point of labor saving but from a standpoint of saving the fabrics from injury due to the chemically treated water.

105 After the contents of the tank have been 110 used to a certain extent so that it is necessary to replenish the supply, a drain plug 31 is arranged in the bottom of the tank 1 whereby the contents can be quickly drawn off and a fresh supply put into the tank. It 115 is believed from the foregoing that I have provided a very economical and simple process together with an apparatus for cleaning garments wherein the finest fabrics can be quickly and easily cleaned without injury to the fabric itself, and the device is of such 120 nature that it can be manufactured and placed on the market at a very low cost.

125 While I have shown and described the preferred embodiment of my invention, it will be apparent that slight changes may be made in the construction when putting the invention into practice without departing from the spirit of the same or the scope of the appended claim.

I claim:

A process of the class described consisting of dipping fabrics in a volatile solvent to provide a protection for the fabrics, then 5 submerging the fabrics in washing water, introducing a pressure in the water for agitating the same through and around the fabrics to remove the volatile solvent and the matter loosened thereby and then removing the 10 fabrics from the washing water and drying them.

In testimony that I claim the foregoing I have hereunto set my hand at Green Bay, 15 in the county of Brown and State of Wisconsin.

GEORGE E. OLSEN.
